(57) **CLAIM**

The ornamental design for an open topped container with a removable partition, as shown and described.

DESCRIPTION

FIG. 1 is a top, left perspective view of my new open topped container with a removable partition design;

FIG. 2 is a left side view thereof, the right-side view being a mirror image;

FIG. 3 is a front elevational view thereof with the partition removed; and,

FIG. 4 is a top plan view thereof with the partition removed.

The broken line showing of the partition in FIG. 1 is included for the purpose of illustrating environmental structure and forms no part of the claimed design.
